DOOR LATCH

Filed May 21, 1926

Stuart W. Parsons.

S. S. May, Limonkey:
His Attorney

Patented Mar. 1, 1927.

UNITED STATES PATENT OFFICE.

STUART W. PARSONS, OF NEW BRITAIN, CONNECTICUT, ASSIGNOR TO THE STANLEY WORKS, OF NEW BRITAIN, CONNECTICUT, A CORPORATION OF CONNECTICUT.

DOOR LATCH.

Application filed May 21, 1926. Serial No. 110,792.

This invention relates to a door latch of the type having a spring projected bolt controlled by an operating member, such as a thumb piece, acting through a lever connected to the bolt.

The aim of the invention is to provide a latch of this sort having various features of novelty and advantage and which is particularly characterized by its simplicity and economy in construction, its durability and its effectiveness in operation.

More particularly, the aim of the invention is to provide a door latch wherein each of the parts may be cheaply made; wherein the parts may be readily assembled; wherein in the bolt has an easy, smooth movement, all danger of the bolt sticking being eliminated; wherein the parts are effectively maintained in their proper relation, so that there is no likelihood of the latch getting out of order, and which may be operated with a minimum amount of effort.

Other objects will be in part obvious and in part pointed out more in detail herein-after.

The invention accordingly consists in the features of construction, combination of elements and arrangement of parts which will be exemplified in the construction herein-after set forth and the scope of the application of which will be indicated in the appended claims.

In the accompanying drawings, wherein I have shown, for illustrative purposes, one of the many embodiments which the present invention may take:

Figure 1 is a side view of my improved latch with the side plate of the casing removed and parts shown in section;

Fig. 2 is a vertical sectional view taken substantially on line 2-2 of Fig. 1, and shows the thumb piece or operating lever and a portion of the handle in dotted lines;

Fig. 3 is a horizontal sectional view taken on line 3-3 of Fig. 1;

Fig. 4 is a front view of the face plate, and illustrates the manner in which the lugs on the sides of the casing engage in the opening in which the head of the bolt is mounted for sliding movement;

Fig. 5 is a view of the removable side plate of the casing; and

Fig. 6 is a perspective view of the guide member for the bolt and to which guide member the removable side plate is adapted

to be secured as hereinafter described more in detail.

Referring to the drawings in detail, *a* denotes, generally, the casing having a front or face plate *b*. *c* is the bolt, the inner end 60 of which is guided by a member *d*. *e* is the spring normally urging the bolt into advanced position, and *f* is a lever operatively connected to the bolt and pivoted on a stud *g*. The operating member, in the present illustrative disclosure, is shown as being in the form of a thumb piece *h* of the usual type, and *i* is a handle connected to the door *k*.

The casing *a* includes two parts, each of which is preferably formed from sheet metal 70 so as to effect economy in manufacture. One of these parts has a side 10, the edges of which are bent over so as to form a top wall 11, a bottom wall 12 and a rear wall 13. The top and bottom walls 11 and 12 have, 75 at their forward ends, lugs 15 which extend through the face plate, and these lugs are peened over as shown. The other part of the casing comprises a removable side plate 16 having, in its rear edge, a notch or recess 17 adapted to closely receive an extension 18 on the rear wall 13. The forward end of the side wall 10 has a projection 19. On the forward edge of the removable side plate 16 is a similar projection 20, and these 80 projections, when the parts are assembled, extend into, and engage the respective side edges of, the opening 21 in the face plate and within which opening the head 22 of the bolt *c* is mounted. By constructing the 85 casing in the manner described, a very economical arrangement is obtained, and the parts may be quickly assembled and are very securely held together. Furthermore, a 90 smooth and solid backing for the bolt is had, it being observed that the bolt is reversible, as shown in Fig. 3, and that, in either position of the bolt, it is guided by the side walls of the casing and the lugs 19 and 20, there 95 being no breaks or cracks in these guiding surfaces so that the bolt will have a smooth action.

The bolt has a shank 25 which may be formed integrally with the head or, if desired, it may be screwed into the head, as 100 shown in Fig. 3. On the rear end of this shank is a button 26. The shank is supported and guided by the member *d*. Between this member and the head 22 is the 105 coiled spring *e*. Interposed between the end 110

of the spring and the member *d* is a washer 27.

The member *d* is preferably formed of sheet metal and has a pair of lugs 28 between which the shank of the bolt is slidably mounted. The member *d* is secured to the wall 10 of the casing by peened over lugs 30. Carried by one of the lugs 28 is a bent over ear 31 having a screw threaded aperture 32 adapted to receive a screw 33 by means of which the removable side plate 16 is secured in place. It will be noted that this member *d*, which is very simple in construction and which may be economically formed, in addition to acting as a guide for the bolt, constitutes an anchor to which the removable side plate 16 is secured.

The lever *f* has a generally U-shaped body with side portions 38 and 39 and a transverse or cross portion 40. The body is of a width substantially co-extensive with the distance between the sides of the casing so that the lever is maintained against lateral canting or tilting. Extending upwardly from one side portion of the U-shaped body is an arm 41 which engages between the member *d* and the button 26 of the bolt. Extending rearwardly from one side of the U-shaped body is an apertured ear 42 through which extends the pivot or stud *g*. One end of this pivot extends through an aperture in the wall 10 and is peened over so as to secure the pivot in place. The other end of the stud is of reduced diameter and is adapted to engage in a similarly sized aperture 48 in the side plate 16 when this plate is in position. It will be noted that the lever *f* is formed of sheet metal so that it may be economically manufactured and, when the parts are in place, the lever is properly guided in its movements.

Adjacent the U-shaped portion of the lever *f* the casing is recessed, as illustrated, so as to accommodate the operating member which is here shown as being in the form of the thumb piece *h* of the usual construction. If desired, a second thumb piece extending to the opposite side of the door, so that the latch may be operated from either side, may be provided, such an arrangement being an old and well known one.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim as my invention:

1. In a door latch of the character described and in combination, a casing including a face plate with an opening for accommodating a bolt, a part formed of sheet metal and having side, top, bottom and rear walls, the latter of which has an extension, and a part comprising a removable side plate having a notch closely receiving said extension, said side wall and said plate each having a projection extending into and engaging a respective side edge of said opening; a bolt having a head slidably mounted in said opening and engaging the smooth, unbroken surfaces provided by the sides of the casing and the said projections; a screw securing said side plate in place; a lever in said casing operatively connected to said bolt, and an operating member for said lever.

2. In a door latch of the character described and in combination, a casing having a face plate provided with an opening for accommodating a bolt, a part formed of sheet metal and having a side wall, and a removable side plate; a spring projected bolt in said casing and having a head extending through said opening; a sheet metal member secured to said side wall and constituting a guide for said bolt and an anchor for said side plate, said member having a pair of lugs straddling and guiding said bolt and a bent over ear with a threaded aperture; a screw extending through said side plate and engaged in said aperture for securing said side plate in place; a lever in said casing operatively connected to said bolt, and means for operating said lever.

3. In a door latch of the character described and in combination, a casing including a face plate having an opening for accommodating a bolt, a sheet metal part having side, top, rear and bottom walls and connected to said face plate, and a removable side plate, said side wall and said side plate each having a projection extending into and engaging a respective side edge of said opening; a spring projected bolt having a head slidably mounted in said opening between said projections; a sheet metal member connected to said side wall and constituting a guide for said bolt and an anchor for said side plate, said member having a pair of lugs straddling said bolt and a bent over ear with a threaded aperture; a screw threaded in said aperture and securing said side plate in place; a lever pivoted in said casing and operatively connected to said bolt, and a thumb piece for operating said lever.

4. In a door latch of the character described, and in combination, a casing having a face plate and a pair of side walls; a bolt slidably mounted in said casing and extend-

ing through said face plate; a lever in said casing having a body with a pair of side portions and a connecting transverse portion, an arm extending from one of said side portions and operatively associated with said bolt, and an apertured ear extending from one of said side portions, said side portions engaging the respective side walls of said casing and being guided thereby; a pivot carried by said casing and extending through said apertured ear, and means for operating said lever.

5. In a door latch of the character described and in combination, a casing having a face plate and a pair of side walls; a spring projected bolt slidably mounted in said casing and extending through said face plate; a pivot carried by said casing; a lever journaled on said pivot and operatively associated with said bolt, and means for operating said lever; said lever comprising a

sheet metal member having a U-shaped body portion, the sides of which are parallel to and slidably engage the respective side walls of said casing, said lever having an arm extending from one of the sides of the body portion and operatively associated with the bolt, said lever further having a rearwardly extending ear journaled on said pivot.

6. In a door latch of the character described and in combination, a casing having a face plate, a part formed of sheet metal and having side, top, bottom and rear walls and a removable sheet metal side plate; a bolt slidably mounted in said casing and extending through said face plate; a sheet metal guide for said bolt and secured to said side wall; a screw for securing said side plate to said guide; a sheet metal lever having an arm operatively associated with said bolt; and a thumb piece engaging said lever.

STUART W. PARSONS.
